UNITED STATES PATENT OFFICE.

CHARLES N. BUSHNELL, OF OQUAWKA, ILLINOIS.

THATCH ROOFING.

SPECIFICATION forming part of Letters Patent No. 606,186, dated June 28, 1898.

Application filed March 1, 1898. Serial No. 672,165. (No model.)

To all whom it may concern:

Be it known that I, CHARLES N. BUSHNELL, of Oquawka, in the county of Henderson and State of Illinois, have invented a new and useful Improvement in Thatch Roofing, of which the following is a specification.

The object of my invention is to provide a cheap form of thatch roofing which is made complete and furnished in rolls and only requires to be laid on the rafters and then attached by wires or otherwise.

It consists in wisps of straw or grass woven into a coarse fabric with successive overlapping layers forming a water-shed surface after the manner of shingles, as will be herein-after more fully described with reference to the drawings, in which—

Figure 1 is a plan view of a section of the thatch roofing. Fig. 2 is an enlarged section taken parallel to the warp-wires, and Fig. 3 is an end view looking sidewise at the wisps.

In the drawings, A B are the wisps of straw, which form the filling or body of the roofing. This is made of any suitable straw, such as that derived from dried grass or grain. Preferably it is made of the straw of the long stiff marsh-grass known as "ramrod-grass," which when dried is very stiff, tough, and well-nigh indestructible from ordinary processes of rotting. The roofing fabric is made two-ply, as shown in Fig. 2, the upper layer of wisps A alternating with the lower layer B, so that said lower layer closes the spaces existing between the wisps of the upper layer, this being an essential condition in making a fabric that will shed water without allowing it to drip through the openings where the warp-wires cross. To make this kind of fabric, there are necessarily employed at least three warp-wires *a*, *b*, and *c*, as shown in Fig. 2, and for weaving it a loom using three heddles is required, and in the manufacture of the warp-wires the heddles are so operated as to cause two warp-wires to be down and one up, alternating with a position in which two warp-wires are up and one down. Thus, referring to Fig. 2, for a top filling-wisp A (see dotted lines) the warp-wires *a* and *c* are down and *b* is up, while for putting in the next filling-

wisp of the lower layer the warp-wire *c* will remain down and *a* will be raised up to *b*, and so on. I do not confine myself to any par-

ticular form of loom for accomplishing this result, as the general principles are well known.

In weaving the fabric I prefer to make it in widths of three feet and to employ sets of warp-wires about six inches apart. These dimensions may, however, be varied at will. The butt-ends of the wisps of straw (see Fig. 1) are made to overlap each other like shingles, and they are overlapped so as to show about six inches, more or less, to the weather. In any one section or width of this fabric all but three sets of warp-wires will be covered up by the overlapped butt-ends of the wisps of straw; but on the upper edge the three sets of warp-wires will be visible. When, however, one section of the fabric is laid upon another section on the roof with a proper lap, the butt-ends of this second section lap over and cover up the otherwise-exposed wires of the first laid section, so that there is no direct exposure of wire, and a uniformed lapped surface of roof is presented to the weather.

In weaving a section of this fabric with overlapped butt-ends all that is necessary to secure this result is to so fill in the wisps of straw between the warp-threads as to allow the butt-ends of the several courses to project entirely above the warp-wires—*i. e.*, the warp-wires are made to grasp the wisps at a point above their lower ends far enough to give the weather exposure below.

In order to make the lower edge of a thatched roof of a proper thickness, the section of fabric which is to go along the eaves has its lower edge made double thickness, which is accomplished by putting two layers on without any difference in lap, as shown at *x* in Fig. 3.

In making my fabric I prefer to use the principle of the loom with a two-ply thickness of thatch, which gives a much closer and tighter fabric that perfectly sheds the water; but I do not confine myself to operating the binding-wires by the loom action, as it is obvious that many of the advantages of my invention might be obtained by stitching the layers of thatch-wisps together by a wire-sewing machine. I may also use cord or any other material for warp-threads in the place of wire.

In applying this portable roof-thatch the fabric which comes in rolls from the loom-

take-up cylinder is made easily portable and is shipped to any point and simply laid on rafters without any sheathing beneath it, there being wrapped across the rafters ¹⁰ 5 porting-wires, to which the thatch fabric is fastened by other wires, and thus the roof is quickly applied, firmly held, and may be easily detached, rolled up, and removed to another point. This latter feature of portability without destruction or damage is a feature of great advantage when temporary shelters are used and moved from time to time or when a tenant moves from one farm to another.

Having thus described my invention, what ¹⁵ 15 I claim as new, and desire to secure by Letters Patent, is—

1. A portable thatch roofing, consisting of wisps of straw or analogous material fastened together by warp wires or cords arranged in ²⁰ 20 series of groups each group containing three or more of said wires or cords to form an imperforate rain-shedding fabric substantially as shown and described.

2. A portable thatch roofing, consisting of ²⁵ 25 wisps of straw, or analogous material, fastened

together in overlapping layers and bound together by wires or cords transversely to the length of the wisps substantially as shown and described.

3. A portable thatch roofing, consisting of ³⁰ 30 wisps of straw or analogous material, fastened together by wires or cords transversely to the length of the wisps, the body part of said wisps being arranged two-ply, or with one wisp in one layer opposite the space between ³⁵ 35 two wisps of the other layer, and the butt-ends of the wisps being arranged in overlapping shingle-like layers substantially as shown and described.

4. A portable thatch roofing, consisting of ⁴⁰ 40 wisps of straw or analogous material, a series of warp wires or cords arranged in sets of three connecting the body of the wisps in two-ply relation, the butt-ends of the wisps being arranged in overlapping shingle-like ⁴⁵ 45 layers substantially as described.

CHARLES N. BUSHNELL.
